[57] CLAIM

The ornamental design for a table leg or similar article, as shown and described.

DESCRIPTION

FIG. 1 is a perspective view of a table leg or similar article showing my design;

FIG. 2 is a left end elevational view;

FIG. 3 is a right end elevational view;

FIG. 4 is a top plan view;

FIG. 5 is a right side elevational view; and

FIG. 6 is a left side elevational view thereof.

The bottom of the table leg or similar article not shown is the same in appearance as the showing made in FIG. 4.

FIG. 1

FIG. 2

FIG. 3

FIG. 4

FIG. 5

FIG. 6
